UNITED STATES PATENT OFFICE.

JOHN J. TOOMEY, OF CHICAGO, ILLINOIS.

STOVE OR RANGE.

Application filed December 7, 1925. Serial No. 73,606.

This invention relates particularly to ranges of the type which are equipped with cooking-tops and ovens.

The primary object of the invention is to embody in a range of this type an improved heating section, so that the range may be used for the purpose of heating a kitchen, as well as for ordinary cooking and baking purposes.

10 The present invention constitutes a modification of the invention described in my application 26,894, filed in the United States Patent Office, April 30, 1925.

15 The invention is illustrated in its preferred embodiment in the accompanying drawings, in which—

Fig. 1 represents a plan sectional view of the improved range, the section being taken approximately as indicated at line 1 20 of Fig. 4; Fig. 2, a broken plan view showing the rear portion of the range; Fig. 3, a broken vertical sectional view taken as indicated at line 3 of Fig. 2; Fig. 4, a vertical sectional view taken as indicated at line 25 4 of Fig. 1; Fig. 5, a broken transverse vertical sectional view taken as indicated at line 5 of Fig. 4; Fig. 6, a broken plan sectional view taken as indicated at line 6 of Fig. 4; and Fig. 7, a broken transverse vertical sectional view taken as indicated 30 at line 7 of Fig. 4.

The drawings show the invention embodied in a gas-range, but it will be understood that other heating elements, for example, electric heating elements, may be substituted for the gas-burners, if desired.

In the construction illustrated, A designates the base-frame of the range supported on legs A'; B designates an oven-unit 40 mounted on one end of the base-frame; and C designates the cooking-top of the range, which, in the illustration given, has a closed central top section C' which surmounts a heating unit C² which is mounted on the 45 other end of the base-frame A and separated from the oven-unit by a warming oven C³. The cooking-top C extends laterally from the oven section B; and the heating section C² is flanked by cooking sections C⁴ and C⁵, the cooking section C⁴ being interposed between the oven B and the heating section C' and surmounting the warming oven C³. While it is preferred to 50 locate the heating section C² in an intermediate position between the cooking sections

C⁴ and C⁵, any desired arrangement may be employed.

The oven-unit B is mounted on one end of the base-frame A in any suitable manner, and preferably comprises an upper main oven and a lower broiler oven (not shown in detail). The cooking-top comprises a perimetral frame 1 which is provided with a rabbet 1^a on which the end-portion of the central plate forming the closed top C' are 60 supported. The frame C is supported at a suitable distance above the base-frame A in any suitable manner. Flanking the central plate C' are the grid-plates 2 and 3 which are disposed above the burner-boxes 2^a and 3^a of the cooking sections C⁴ and C⁵. These burner-boxes flank the upper portion of the heating section C².

Extending across the front of the range is a gas-manifold 4 which supplies pipes leading to burners 5 located in the upper portion of the heating section and burners 5^a located in the cooking sections C⁴ and C⁵. The pipes which supply said burners are controlled by means of valves 6. The cooking sections which flank the heating section may be of any desired construction. The rear wall 7 of the range extends above the cooking space 8 and is equipped with a shelf 9 which is interposed between the oven and a sheet-metal standard 10 which is disposed at one end of the range. The closed top C' of the heating section C² is provided with removable lids 11 which are located above the burners 5.

The heating section C² of the range preferably comprises a front frame, or plate, 12, which may, if desired, be equipped with a door 12^a. The heating section is provided with lateral walls 13 which may be 90 provided at their lower portions with air inlets 13^a. The door 12^a may also be provided with air inlets 14. Flanking the upper portions of the lateral walls 13 of the heating section are air conduits 15 formed by spaces between the plates, or walls, 16, which extend from the front wall of the range to the rear wall of the range. The members 16 have lower walls 16^a which are cut away at their front portions 16^b, 100 as indicated in Fig. 4, thus providing for ingress of air at the front ends of the conduits 15.

Disposed parallel with the rear wall of the range is a supplemental heater D which 110

comprises a front air-flue D', a rear air-flue D², and an intermediate gas-flue D³. The gas-flue D³ is provided with baffle-plates 17 which cause the products of combustion to pursue a circuitous course. The front air-flue D' is provided at its upper end with air outlets 18, and the rear air-flue D² is open at its upper end, as indicated at 19. The rear air-flue D² is also open at its lower end, as indicated at 19a.

The range is equipped in front of its rear wall with a transverse air-flue 20 which is in communication with the rear ends of the air-flues 15; and the transverse air-flue 20 15 communicates through an air passage 21 with the lower portion of the front air-flue of the supplemental heater D. The inner chamber of the heating section C² communicates through a gas-passage, or gas-flue, 22, 20 with the gas-flue D³ of the supplemental heater, the passage 22 extending through the front air-flue D' of the supplemental heater.

The upper portion of the gas-flue D³ 25 of the supplemental heater communicates through a gas-flue 23 (Fig. 2) with an outlet flue 24 which is in communication, through a gas-passage 25 with the gas-flues 26 of the oven. The flue 24 may connect with a pipe (not shown), leading to a chimney.

From the description given, it will be understood that when the burners 5 in the heating section C² are lighted, the products of combustion will pass therefrom through the passage 22 into the gas-flue D³ of the supplemental heater, and thence through the flue 23 to the main outlet gas-flue 24 of the range. Also, air will enter the air-flues 15 (through passages 16^b) and will circulate through said flues in the transverse flue 20, and thence through the passage 21 to the front air-flue D' of the supplemental heater, the heated air passing out through the passages 18 into the room. Also, air will circulate upwardly through the rear air-flue D² 40 of the supplemental heater.

It will be noted that in the present construction, the burners 5 are disposed near the upper portion of the heating section C² and 50 may be used for cooking purposes. In this construction, the burners 5 are disposed beneath the closed top C', there being no intervening wall between the burners and the closed top. If desired, the lids 11 may be removed and cooking vessels may be supported in the openings which the lids normally cover. In practice, it is found that the heating section C², taken in connection 55 with the supplemental heater D, will suffice to supply a sufficient amount of heated air 60 to heat a small kitchen which is not equipped with other heating means.

While the heating capacity of the present 65 range is somewhat less than that of the construction described in the above-mentioned

application, the present construction is somewhat cheaper and affords ample capacity, ordinarily for apartment kitchens.

The foregoing detailed description has been given for clearness of understanding 70 only, and no unnecessary limitations should be understood therefrom, but the appended claims should be construed as broadly as permissible, in view of the prior art.

What I regard as new, and desire to set 75 out by Letters Patent, is:

1. A range comprising a cooking-top provided with a heating section having a closed-top and an outlet passage, a heating element in said section immediately below said closed-top, air-flues adjacent said heating section provided with an air outlet; and a supplemental heater disposed back of said range and having a flue with which said outlet passage communicates and having an air-flue with which said air outlet communicates. 80

2. A range comprising a cooking-top provided with a heating section having a closed-top and an outlet passage, a heating element in the upper portion of said section adjacent said closed-top, rearwardly extending air-flues flanking the upper portion of said heating section provided with an air outlet; and a supplemental heater disposed behind and parallel with the back of said range and having a flue with which said outlet passage communicates and having an air-flue with which said air outlet communicates. 90

3. A range comprising a base, an oven-unit mounted on one end of said base and provided with gas-flues, a cooking-top extending laterally from said oven and having a closed-top section, a heating section mounted on said base and surmounted by said closed-top section, a gas-burner in the upper portion of said heating section in unobstructed relation to said closed-top, whereby the heating section may be used as a cooking section, air-flues adjacent the sides of said heating section; and a supplemental heater at the rear portion of said range provided with a gas-flue communicating with the burner-chamber of said heating section and provided with an air-flue communicating with said first-named air-flues, and an outlet gas-flue communicating with the gas-flues of said oven-unit and with the gas-flue of said supplemental heater. 100

4. A range comprising a base-frame, an oven-unit mounted on one end thereof and provided with gas-flues, a heating section mounted on the other end thereof and separated from the oven-unit by a space, a cooking-top extending laterally from said oven-unit and having a closed intermediate top section forming the top of said heating section, air-flues flanking the upper portion of said heating section and provided at the rear portion of the range with an air outlet, a burner-box interposed between the oven-unit 105 115 120 125 130

- and the adjacent air-flue of the heating section, a burner-box disposed at the other side of the heating section adjacent the air-flue thereat, a gas-burner in the upper portion of 5 said heating section disposed adjacent said closed-top, whereby said heating section may be employed as a cooking section; gas-burners in said burner-boxes; and a supplemental heater parallel with the rear side of 10 the range having a gas-flue communicating with the burner-chamber of said heating section and having an air-flue communicating with the air outlet of said first-named air-flues, a gas outlet flue connected with the 15 gas-flues of the oven, and a gas-flue connecting the gas-flue of said supplemental heater with said gas outlet flue.
5. A range comprising a base-frame, an oven-unit mounted on one end of said frame 20 and provided with gas-flues, a heating sec-
- tion comprising a chamber mounted on said frame and spaced some distance from said oven, said chamber being provided at its lower portion with air inlets, a cooking-top extending laterally from said oven-unit and having a closed section surmounting said chamber, a burner disposed in the upper portion of said chamber below said closed-top, air-flues flanking the upper portion of said chamber and having an air outlet at the rear 25 side of the range; and a supplemental heater disposed back of and parallel with the rear side of the range and having a gas-flue communicating with the rear upper portion of said first-named chamber and having an air-flue communicating with said air outlet, and a gas outlet flue communicating with the gas-flues of the oven and with the gas-flue of said supplemental heater.

JOHN J. TOOMEY.
